(57) CLAIM

The ornamental design for a base for supporting a scope on a rifle, as shown and described.

DESCRIPTION

FIG. 1 is a perspective view of my design for a “base for supporting a scope on a rifle”;

FIG. 2 is a rear elevational view thereof;

FIG. 3 is a front elevational view thereof;

FIG. 4 is a top plan view thereof;

FIG. 5 is a left elevational view thereof, and the right elevational view being a mirror image thereof; and,

FIG. 6 is a bottom plan view thereof.
